ELECTRICAL CONNECTER

Harry A. Douglas, Bronson, Mich.

Application May 9, 1932, Serial No. 610,009

2 Claims. (Cl. 173—328)

This invention relates to methods of producing electrical connectors.

Among other objects, the invention aims to provide an improved connector more particularly for use as a line connection between current conducting wires.

As a further object, the invention is inclusive of a simple and economical method of producing my improved connector.

10 By the practice of my invention, the conductor by which the electrical connection between the current conducting wires is made, is completely enclosed within a seamless insulating body, while at the same time passages are provided there-through for the reception of the line terminals.

The invention will be understood by reference to the illustrative embodiment and exemplary steps shown in the accompanying drawing, in which—

20 Figure 1 is a side elevation of a connector made in accordance with my invention with the cores still in place;

25 Figure 2 is a longitudinal section of the structure of Figure 1 on an enlarged scale, with one of the cores removed, and is also a sectional view taken on the line 2—2 of Figure 3;

Figure 3 is a section taken on the line 3—3 of Figure 2 with both cores removed;

30 Figure 4 is an elevational view similar to Figure 1, but with both cores removed and showing, by dotted lines, how the terminals are received in the connector; and

Figure 5 shows a preferred preliminary step in the practice of my invention.

35 In accordance with my invention, I provide a conductor 1 which is advantageously made of brass and may have a central oblong portion 2 and turret-shaped end portions 3. Parallel apertures 3a, in this instance cylindrical, in the oblong por-

40 tion 2 permit the passage therethrough of the conventional bulbous terminals 4 of insulated current conducting wires 5 which are yieldingly retained in the conductor 1 by means next described and are put into electrical connection by

45 said conductor.

For yieldingly retaining the terminals 4 in the conductor 1, I may provide a dome shaped detent 6 which is yieldingly projected into each of the apertures 3a by a coil spring 7 housed in the turret-shaped portions 3 of the conductor 1 and pressing upon the detent through the intermediation of an annular flange 8 formed on the detent, which limits the movement of the detent into the apertures 4. The detent 6 thus snaps into the annular groove 9 in the bulbous terminals.

To afford a seamless insulating covering for the conductor 1, as a preferred first step in the practice of my invention (see Figure 1), I provide two cylindrical steel cores 10 having a central portion 11 shaped somewhat similarly to the terminals 4. The cores 10 terminate at one end in a portion 12 of reduced diameter and at the other end in a portion 13 of slightly larger diameter than the central portion 11. The central portion 11 has therein an annular groove 14 which is adapted to receive the detent 6 and locate the cores 10 in the conductor 1 in position corresponding to the positions of the terminals 4.

It will be noted, as shown in Figures 1 and 5, that the cores 10 are placed in the conductor 1 in reversed relationship and the enlarged portions 13 of the cores limit their insertion in the conductor to an extent that the groove 14 just registers with the detent 6. When the cores have been inserted in the apertures 3a of the conductor 1 as just described and as shown in Figure 5, an insulating body 15 composed of a phenolic condensation product, for example, is molded about the conductor and the cores by suitable molding means (not shown) to produce the intermediate structure shown in Figure 1 in which the conductor is completely covered by a seamless insulating body, while at the same time apertures through this body are effected by the cores 10, the insulating body 15 being molded to terminate short of the ends 12 and 13 of the cores and the cores thus protruding through upon each side of the conductor 1.

The provision of the reduced end 12 of the cores causes a shoulder 16 to be produced at one end of each of the apertures 3a which limits the insertion of the terminals 4 therein to an extent where the grooves 9 in the terminals just register with the detents 6.

The reduced portions 12 which protrude through the openings 12a also facilitate the removal of the cores from the intermediate structure shown in Figure 1. As shown in Figure 2, one of these cores has been removed, and in Figures 3 and 4 both cores have been removed, thus providing passages 17 and 18 through the insulating body 15 upon each side of the apertures 3a in the conductor 1 and registering therewith for the reception of the terminals 4. Obviously, the passages 17 have been produced by the enlarged portions 13 of the cores and the passages 18 by the intermediate portions 11 of the cores, the latter portions being desirably of exactly the diameter of the largest diameter portion 19 of the bulbous tips of the terminals 4.

The passages 17 are desirably slightly larger to permit ready insertion of the terminals therethrough.

5 The springs 7 may be first inserted in the hollow turrets 3 of the conductor 1 through openings 20 in the outer ends of the turrets, and the margins of these apertures then bent inwardly to retain the springs therein. The openings 20 are then desirably closed by a plug 21 of solder or the like, 10 to prevent the material of the insulating body 1 while still soft, from flowing into the turrets 3.

15 The invention is not limited to the specific details of construction or the sequence of steps described, but such changes may be made as fall 20 within the scope of the following claims without departing from the invention.

I claim:

1. An electrical connector including an elongated metallic conductor block having adjacent

apertures extending transversely therethrough for the reception of terminal plugs and provided with a housing at each end with a spring pressed detent mounted in the housing entering the contiguous terminal receiving passage to engage and removably retain the terminal therein, said conductor block and spring housing entirely imbedded in a molded body of insulating material provided with oppositely disposed openings registering with the respective terminal apertures in the conductor block and provided with oppositely disposed extensions opposite each opening having a bore therein forming a continuation of the contiguous terminal receiving aperture.

2. The structure of claim 1 wherein the outer end of each bore is provided with a perforated end closure limiting the passage of a terminal plug therethrough.

HARRY A. DOUGLAS.
